UNITED STATES PATENT OFFICE.

ROBERT L. WYATT, OF FLORENCE, SOUTH CAROLINA, ASSIGNOR, BY DIRECT AND MESNE ASSIGNMENTS, TO SIXTY-SEVEN SHINGLE COMPANY, OF FLORENCE, SOUTH CAROLINA, A CORPORATION OF SOUTH CAROLINA.

SHINGLE.

Application filed November 19, 1923. Serial No. 675,713.

To all whom it may concern:

Be it known that I, ROBERT L. WYATT, a citizen of the United States, residing at Florence, in the county of Florence and State of South Carolina, have invented certain new and useful Improvements in Shingles, of which the following is a specification.

My invention relates to improvements in shingles, and it consists in the combinations, construction and arrangements herein described and claimed.

An object of the invention is to provide a shingle which is formed in such manner that a plurality of shingles may be laid in the construction of a roof with each shingle engaged adjacent to its lower ends by the shingles adjacent thereto and held against bending or curling up by the adjacent shingles whereby a substantially leak proof and durable roof may be constructed with an expenditure of relatively little time and labor.

Other objects and advantages will be apparent from the following description considered in conjunction with the accompanying drawings in which,

Figure 1 is a fragmentary perspective view of a roof composed of shingles embodying the invention,

Figure 2 is a fragmentary plan view of the roof,

Figure 3 is a section along the line 3--3 of Figure 2,

Figure 4 is a plan view of my improved shingle.

In carrying out the invention, I make use of a square sheet of a suitable flexible or pliable material, which may be a light gauge metal, or any one of the well known composition materials which are used in the construction of shingles. A shingle formed of the square sheet is indicated generally at 1 in Figure 4 and in forming this shingle, one of the corner portions of the square sheet is cut off adjacent to its extremity along a line extending transversely of the corner portion as indicated at 2. A pair of inwardly extending aligned notches or slits 3 are formed in the corner portion in parallel relation to the line 2, thus providing a body portion 4, which is substantially square and an attaching portion 5 which is trapezoidal in shape and is merged into the body

by a relatively short neck portion 6, as indicated at 7 in Figure 4. The converging side walls of the body 4 which are merged into the walls of the slits 3 are convexly curved at their juncture with the adjacent or inner side walls of the slits 3, as indicated at 7 in Figures 1, 2 and 4.

The body 4 is provided with a nail receiving aperture 8 through each of the opposite corners which are adjacent to the attaching portion 5. The attaching portion 5 is bent under the body 4 along a line substantially coincident with the line of the inner walls of the slits 3, whereby the adjacent ends of the curved portions 7, of the said converging side walls of the body 4 will be connected together along a substantially straight line as indicated at 9 in Figures 1 and 2.

From the foregoing description of the various parts of the device the operation may be readily understood. In forming a roof construction with my improved shingles, the shingles are laid diagonally. Eave and edge strips 10 and 11 respectively may be used. Each course is provided by placing one of the shingles 1 directly above a shingle 1 of the next lower course and arranging the adjacent shingles of the diagonally extending rows so that the adjacent shingles at opposite sides of the lower end portion of each shingle extend partially underneath the body 4 and enter the slits 3, engaging with the bent under fastening portion 5 and thus securely holding down the lower end portion of the body 4. It, of course, will be understood that nails 12 are driven through the apertures 8 of each shingle as the shingle is laid, whereby each shingle of the completed roof will be held in place by four nails and additionally by the engagement with the bent under attaching portion at the lower end thereof of the adjacent portions of the next lower shingles in the diagonally extending rows. Since the lower end or exposed portion of each shingle has no sharp corners, it will be manifest that the lower or exposed portion of the shingle is not likely to be bent or curled up because of the action of the elements and a roof composed of the improved shingles, therefore, will be substantially leak proof for a relatively long time.

Obviously my invention is susceptible of embodiment in forms other than that illustrated in the accompanying drawings and I, therefore, consider as my own all modifications and adaptations thereof which fall within the scope of the appended claims.

I claim:

1. A shingle formed of a substantially rectangular sheet of flexible material having aligned slits in the converging sides of a corner portion thereof, thus providing a body portion, and an attaching portion merged into the body portion by a connecting portion which is of less width than the widest part of the attaching portion, said attaching portion being adapted to be bent under the body, said attaching portion having the outer end thereof cut off along a line extending transversely thereof.
2. In a roof construction, a plurality of shingles, each formed of a substantially square sheet of flexible material provided with aligned slits in converging side walls of a corner portion thereof, the extremity of said one corner portion thereof being cut off along a line extending transversely of the corner portion, thus defining a body

portion, a short neck portion and a trapezoidal locking portion, the adjacent walls of each slit and the body portion being convexly and regularly curved at their juncture with one another, said shingles being laid in courses extending horizontally of the roof with adjacent corner portions of adjacent shingles of each course in abutting relation at their extremities and in underlying relation to the body of the adjacent shingle of the course next thereabove, the last named shingle being disposed with the locking portion thereof lowermost and bent underneath the body portion of said last named shingle along the line of the inner side walls of the slits therein, the lateral edge portions of the locking portion of said last named shingle underlying adjacent edge portions of the lower portions of the bodies of the adjacent shingles of the next lower course, whereby the lower end portion of each shingle tends to hold the lower end portions of the adjacent shingles of the next lower course against upward movement from the roof and the exposed portion of each shingle is free from pointed projecting portions.

ROBT. L. WYATT.
